BROADBAND MICROWAVE POINT CONTACT RECTIFIER

Carson E. Weaver and John G. Hambor, Bethlehem, Pa., assignors to Gahagan, Inc., Esmond, R.I., a corporation of Pennsylvania

Application March 5, 1957, Serial No. 644,158

3 Claims. (Cl. 317—236)

This invention relates to point contact rectifiers, and more particularly to a point contact rectifying unit of the type employing the combination of a body of semiconductor material, such as a piece of germanium crystal and a metallic pointed wire element which engages the surface of the semiconductor material.

A main object of the invention is to provide a novel and improved point contact rectifier unit which is simple in construction, which is easy to manufacture, and which provides efficient operation throughout a substantial portion of the radio frequency spectrum, namely, through the portion of the radio frequency spectrum from 1,000 megacycles per second to 10,000 megacycles per second.

A further object of the invention is to provide an improved point contact rectifier of the germanium crystal type, said rectifier being relatively inexpensive to manufacture, being rugged in construction, and being especially adapted for use in the portion of the radio frequency spectrum from 1,000 megacycles per second to 10,000 megacycles per second, the improved rectifier unit providing efficient performance with low noise and with relatively high sensitivity.

A still further object of the invention is to provide an improved point contact rectifier unit of the germanium crystal type which is designed to demodulate radio frequency signals in the spectrum range of from approximately 1,000 megacycles per second to approximately 10,000 megacycles per second, the rectifier unit providing relatively high sensitivity with low noise, and having high burnout capability.

A still further object of the invention is to provide an improved point contact rectifier of the type comprising a semi-conductor material, in the form of a crystal, which is engaged by a pointed metallic wire, the improved point contact rectifier being economical to manufacture, providing high conversion gain with low noise, and being reversible so that it may be reversibly connected to a conventional contact socket without requiring rewiring of the socket or any major modification of the point contact rectifier unit.

Further objects and advantages of the invention will become apparent from the following description and claims, and from the accompanying drawings, wherein:

Figure 1 is a perspective view of one form of improved point contact rectifier unit constructed in accordance with the present invention;

Figure 2 is a vertical cross-sectional view taken on the line 2—2 of Figure 1;

Figure 3 is a perspective view of a further form of the improved point contact rectifier unit of the present invention; and

Figure 4 is a vertical cross-sectional view taken on the line 4—4 of Figure 3.

Investigation of semiconductor materials has shown that germanium is best suited as the material from which to construct a point contact crystal rectifier element for use in demodulating radio frequency signals in the fre-

quency spectrum from about 1,000 megacycles to about 10,000 megacycles, namely, in the microwave portion of the radio frequency spectrum. The required semiconductor material consists of germanium metal, grown as a single crystal and "doped" by adding controlled amounts of impurities from the fifth column of the Periodic Table of the Elements, such as arsenic, antimony, and bismuth. The result of proper "doping" of the germanium metal will yield germanium of a resistivity of approximately 0.004 ohm-centimeter to 0.009 ohm-centimeter, which falls into the range of resistivity required to provide the necessary physical parameters of the semiconductor, that is, adequate mobility of minority carriers and bulk resistance, as required in the fabrication and utilization of the device.

Referring to the drawings, and more particularly to Figures 1 and 2, one form of point contact rectifier unit constructed in accordance with the present invention is designated generally at 11. The rectifier unit 11 comprises a cylindrical sleeve-like ceramic holder 12 which is formed with internal threads 13 and which is formed at its intermediate portion with a relatively small aperture 14 to allow the holder to be filled with wax during the latter stages of fabrication of the rectifier unit, as will be presently described.

Designated at 15 is a top conducting terminal which is formed with an externally threaded reduced bottom end portion 16 threadedly engageable in the top end of the ceramic sleeve member 12. Designated at 16 is a base contact terminal having a reduced externally threaded portion 17 which is threadedly engageable in the lower end of the ceramic sleeve 12, as is clearly shown in Figure 2.

The base contact terminal 16 is formed with the axial, depending contact stud element 18.

Designated at 19 is a pellet of germanium metal of proper physical characteristics, as described above, the pellet being cut to a thickness of approximately 0.015 inch and being of suitable shape to fit onto the surface of the reduced portion 12 of base contact terminal 16. For example, the pellet 19 may be square and may have sides of approximately 0.050 inch in length. The pellet 19 is conductively secured to the top surface of the base contact terminal 16, as by soldering the pellet to said top surface.

The top exposed surface of the germanium pellet 19 must be substantially free of contaminants, and decontamination thereof may be achieved by any one of a number of processes well known in the art of semiconductor manufacture.

The top conducting terminal 15 is formed with an axial bore 20, and positioned in said bore 20 is a brass whisker stud 21 which is firmly held in a desired position in the bore 20 by a set screw 22 provided in the wall of the terminal 15, as is clearly shown in Figure 2. The metal wire whisker, shown at 23, consists preferably of copper wire of a diameter between 0.003 inch and 0.005 inch, which is formed into the customary C-shaped or S-shaped whisker element. The top end of the whisker member 23 is secured axially in the bottom end of the stud member 21 in any suitable manner, as by welding, soldering, or the like. Thus, an axial recess or bore may be formed in the lower end of the stud 21 into which the end of the wire member 23 is inserted and is rigidly secured, as by welding or soldering.

The free end of the wire member 23 is pointed, either by grinding same to form a conical pointed tip on said free end, or by shearing the wire at an angle of approximately 60°. Either method will produce a suitable point.

In the assembly of the point contact rectifier 11, the stud 21 is pushed through the bore 20 until the copper whisker wire 23 makes physical contact with the germanium pellet 19. After contact has been made, the stud 21 is pushed inwardly a slight amount to add sufficient compression on the metal wire whisker 23 to insure mechanical stability of the contact between the pointed end of the copper whisker wire 23 and the germanium pellet 19. To provide for added mechanical stability and moisture protection, the inside of the sleeve member 12 is then filled with suitable insulating material, for example, wax. Thus, the wax is introduced into the ceramic sleeve 12 through the aperture 14, to achieve the desired wax impregnation of the interior of the sleeve member.

Referring now to Figures 3 and 4, the point contact rectifier unit is designated generally at 11' and comprises a cylindrical ceramic sleeve-like body 12' which is internally threaded and which threadedly receives at its lower end the bottom contact terminal 16' and which threadedly receives at its top end the upper contact terminal 15'.

As will be readily apparent from Figure 4, the top and bottom contact terminals 15' and 16' are identical in construction and are respectively formed with the reduced axial shank portions 35' and 36'. The respective members 15' and 16' are thus formed with respective annular flange elements 24' and 25' which are located adjacent the top and bottom ends of the ceramic sleeve member 12'.

The two opposite ends of the ceramic body 12' are suitably metalized, for example, are platinized, to provide metal soldering surfaces at said opposite ends. The flanges 24' and 25' are soldered to the respective top and bottom ends of the body 12' to provide a hermetic seal between the top and bottom members 15' and 16' and the respective top and bottom ends of the ceramic body 12'. Thus, the flanges 24' and 25' are sealed to the top and bottom ends of the ceramic body 12' by respective annular masses of solder, shown at 26' and 27' in Figure 4.

The lower contact terminal 16' is formed with an axial bore 28' in which is located a contact stud 29' having a germanium pellet 19' of proper physical parameters, described above, soldered to its top end. The stud 29' is forced through the bore 28' after the terminal elements 15' and 16' have been hermetically sealed to the top and bottom ends of the ceramic body 12', as above described. A solder seal 30' is then made between the inside surface of the bore 28' and the lower end of the stud 29'.

The stud 29' is preferably provided with a fluted external surface so that it will frictionally interengage with the inside surface of bore 28' and become mechanically locked therewith after its has been forced into bore 28' to its desired position.

The upper parallel member 15' is formed with an axial bore 31' in which is positioned a stud member 21', to the lower end of which is secured the copper whisker wire, shown at 23', said whisker wire having a pointed end which engages the surface of the germanium pellet 19'. In the assembly, the stud 21', carrying the copper whisker wire 23', is forced through the bore 31' until electrical contact is made between the pointed end of the whisker 23' and the top surface of the germanium pellet 19'. The stud 21' is preferably provided with a longitudinally fluted external surface, similar to that provided on the stud 29', so that the stud 21' will frictionally interengage with the inside surface of bore 31' and will be mechanically locked therewith to provide mechanical stability. A solder seal 32' is made between the inside surface of bore 31' and the top end of the stud 21'.

Designated at 33' is an electrical conducting adapter which may be selectively engaged on the axially projecting outer end portion of either terminal element 15' or terminal element 16' to provide for electrical polarity reversal, whereby the rectifier may be reversibly connected to a conventional contact socket. The conductive adapter 33' is coextensive in length with the axially pro-

jecting outer end portions of terminals 15' or 16', as is clearly shown in Figure 4.

In the case of both of the modifications above described, after the mechanical assembly is completed, the point contact rectifier unit is preferably electrically formed in the manner described in our copending application Serial No. 630,166, filed December 24, 1956. This is accomplished by inserting the assembled rectifier unit into a standard mixer which is electrically connected to a conventional electrical device designed to indicate the intermediate frequency impedance and then applying controlled electrical pulses of about one quarter of an ampere to an ampere of a duration of one tenth of a second to a second to the rectifier in the forward direction of the semi-conductor. For the results here desired, the forming current need not be more than one half an ampere. The application of the forming current to the point contact rectifier reduces the intermediate frequency impedance from an initial value of from about 600 to 800 ohms to the required value of between 350 and 450 ohms. During the electrical forming process, current densities of the order of several thousand amperes per sq. inch are achieved at the pointed end of the whisker wire, which in turn produce very high temperatures in the region of contact of the whisker wire and the germanium pellet. At these elevated temperatures, when a copper or brass wire is used, copper atoms from the whisker wire diffuse into the n-type germanium. These copper atoms are of acceptor impurity nature, thus forming a small p-n junction in the vicinity of the point contact. By controlling the magnitude of the forming current, the affected area of the junction is controlled, which in turn provides control over the resultant junction capacitance. It is important that this junction capacitance be held to a minimum in the electrical forming process in order to achieve low values of conversion loss, or conversely, high values of conversion gain.

The whisker wire may be of any suitable metal having the desired physical characteristics, such as platinum, gold, nickel, titanium, or any other suitable metal suitable for operation in the desired portion of the radio frequency spectrum, for example, in the portion of said spectrum from approximately 1,000 megacycles per second to 10,000 megacycles per second. A wire having substantial copper content is preferable, however, in order to achieve the low enhancement current characteristics described in our aforesaid copending application.

The point contact rectifier units of the present invention will operate throughout the radio frequency spectrum from 1,000 megacycles per second to 10,000 megacycles per second in the standard types of mixers now used by the Armed Services and which are approximately designated "JAN Approved." At the present time no one type of silicon mixer diode can perform throughout the above cited frequency range. For instance a 1N21 type silicon mixer diode is employed for the range between 1,000 to 4,000 megacycles per second; a 1N150 type silicon mixer diode is employed from 4,000 to 6,000 megacycles per second; and a 1N23 type silicon mixer diode is employed from 6,000 to 10,000 megacycles per second.

While certain specific embodiments of an improved point contact rectifier unit have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A reversible point contact rectifier for operation throughout the radio frequency spectrum from 1,000 to 10,000 megacycles per second, comprising a sleeve-like holder of insulating material, a first metallic stud member secured in one end of the holder and having an axially projecting external shank portion, a germanium crys-

tal element secured on the inner surface of said stud member, a second metallic stud member secured in the opposite end of said holder and having an axially projecting external shank portion identical with the first-named shank portion, a copper wire member secured to the inner end of the second stud member, a point on said wire member engaging and fused with the surface of said crystal element, means hermetically sealing said stud members to the opposite ends of said holder, and a metallic contact sleeve detachably secured on one of said shank portions, said contact sleeve being substantially coextensive in length with said shank portions and being selectively engageable thereon, whereby the rectifier may be reversibly connected to a contact socket.

2. A reversible point contact rectifier comprising a holder of insulating material, a first conductive contact member mounted on one end of said holder, a second conductive contact member mounted on the opposite end of said holder, a semi-conductive crystal element mounted on said first contact member, a whisker wire mounted on said second contact member and having an end engaging said crystal member, each of said contact members having a shank portion projecting endwardly from said holder and the shank portions being of the same length and external shape, and a contact sleeve of the 25

same length as, and detachably secured to, one of said shank portions, said sleeve being selectively engageable with either of said shank portions to permit reversal of the rectifier in a socket.

5. A reversible point contact rectifier comprising a tubular holder of insulating material, having opposite ends, a pair of contact members one mounted on and forming a closure for each of said ends, each of said members having a cylindrical shank portion projecting 10 endwardly from said holder and said shank portions being of the same diameter and length, a semi-conductive crystal element mounted on one of said members and a whisker wire mounted on the other of said members and engaging said element, and a contact sleeve of the same length as, and detachably secured to, one of said shank portions, said sleeve being selectively engageable with either of said shank portions to permit reversal of the rectifier in a socket.
